UNITED STATES PATENT OFFICE.

CHARLES G. HILL, OF NOTTINGHAM, ENGLAND.

DESIGN FOR A RUFFLING OR RUCHING.

SPECIFICATION forming part of Design No. 21,447, dated April 5, 1892.

Application filed March 8, 1892. Serial No. 424,290. Term of patent 9½ years.

To all whom it may concern:

Be it known that I, CHARLES G. HILL, a subject of the Queen of Great Britain, residing at Nottingham, England, have invented and produced a new and original Design for a Ruffling or Ruching, of which the following is a specification, reference being had to the accompanying drawing, which illustrates a plan view of a portion of the ruffling or ruching embodying my design.

The design consists of a series of practically-angular figures A, seemingly arranged diagonally across the upper edge of a figure

B, simulating a strip of fabric, one edge of the angular figures being represented as in 15 feathery outline, the whole design presenting a series of angular figures having somewhat of a solid appearance substantially surrounded by feathery borders.

I claim—

The design for a ruffling or ruching, substantially as shown and described.

CHARLES G. HILL.
